UNITED STATES PATENT OFFICE.

EARL F. KIMBALL, OF BROOKLINE, MASSACHUSETTS.

INTERNAL-COMBUSTION ENGINE.

1,249,418.

Specification of Letters Patent. Patented Dec. 11, 1917.

Application filed April 18, 1916. Serial No. 92,005.

To all whom it may concern:

Be it known that I, EARL F. KIMBALL, a citizen of the United States, residing at Brookline, county of Norfolk, State of Massachusetts, have invented an Improvement in Internal-Combustion Engines, of which the following description, in connection with the accompanying drawings, is a specification, like characters on the drawings representing like parts.

This invention relates to internal combustion engines and has for its object to provide an engine with a slow-rotating cam shaft constructed to provide the desirable quick-opening and closing of the valves notwithstanding the relatively-slow rotary movement thereof.

The ordinary four-cycle internal combustion engine is provided with a cam shaft by which the valves are opened and closed and which is geared to the crank shaft by a two-to-one gearing so that the cam shaft moves at one-half the speed of the crank shaft. The cam shaft is provided with cams so constructed that each rotation of the cam shaft will open each valve once. It is desirable that the valves should open and close with a quick movement and the cams that are used on the cam shaft for operating the valves are shaped to give as quick an opening and closing movement as possible, but when the engine is running very rapidly and the cam shaft has a correspondingly rapid speed of rotation, the more or less abrupt cams on the cam shaft are apt to cause the valves to jump which results in an uneven operation of the engine. I obviate this by providing a multiple cam for each valve which is constructed to secure the opening and closing of the valve a plurality of times during each rotation of the cam and I interpose a train of gearing between the crank shaft and the cam shaft by which the cam shaft will be rotated at a very much slower speed than the crank shaft. By this means a slow-moving cam is provided which nevertheless will give the requisite quick-opening and closing movement to the valve.

In order to give an understanding of my invention, I have illustrated in the drawings a selected embodiment thereof which will now be described, after which the novel features will be pointed out in the appended claim.

Figure 1 of the drawings is a vertical sectional view through an internal combustion

engine embodying my invention with a portion of the crank casing shown in elevation;

Fig. 2 is a section on the line 2—2, Fig. 1;

Fig. 3 is a detail view of the end of the valve stem.

Fig. 4 is a section on the line 4, Fig. 3.

I have shown at 1 an internal combustion engine having the cylinder 2 in which operates the piston 3, said piston being connected by a connecting rod 4 to the crank 6 of the crank shaft 5. The cranks operate in the usual crank casing 7. 8 is one of the valves (either the inlet valve or the outlet valve) controlling the port 41 to the cylinder. This valve is herein shown as a piston valve provided with a port 42 by which communication is established between the manifold 43 and the port 41. The valve is shown as having a stem 9 secured thereto which is acted on by a spring 44 as usual. The parts as thus far described are or may be of any usual construction and form no part of my present invention. The valves for each cylinder are actuated from a cam shaft 10 by suitable cam mechanism which embodies my invention. The cams which I have herein illustrated for the valves are shown at 11 and these are in the nature of multiple cams, that is, each cam is provided with a plurality of cam projections 12, each one of which acts on the valve stem to open the valve as the cam is rotated. In the illustrated embodiment of my invention the cam 11 has twelve such cam projections 12 so that upon each rotation of the cam the valve 8 will be operated twelve times. Each cam projection is provided with the abrupt cam face 13 which acts on the toe or dog 14 at the end of the valve stem thereby to raise the valve as the cam rotates anti-clockwise. Fig. 1. Each cam projection is also provided with the radially-extending face 15 so that as soon as the cam projection has passed the toe 14, the valve can close quickly.

Any suitable gearing may be employed to rotate the cam shaft 10 at the proper speed relative to that of the crank shaft which is necessary to secure the correct timing of the valve action. Where the cam member 12 has twelve cam projections, then it will be necessary to rotate the cam shaft once only during each twenty-four rotations of the crank shaft. The gearing herein shown for connecting the crank shaft to the cam shaft comprises a bevel gear 16 fast on

the cam shaft meshing with the gear 17 fast on a cross shaft 18 that is journaled in suitable bearings 19 carried by the crank casing 7. This shaft 18 has a worm wheel 5 20 thereon which meshes with a worm 21 fast on the end of the crank shaft 5. This worm gearing provides a simple device for driving the cam shaft from the crank shaft at the proper reduced speed. The toe 14 10 will be preferably yieldingly connected to the valve stem 9 so as to permit the cam 11 to turn backwardly when in the position shown in Fig. 1 without injuring the valve rod in case the engine back fires. The lower 15 end of the valve stem 9 is shown as forked, as at 23, and the toe 14 is provided with an extension 24 that is received between the arms of the fork 23. This toe member 14 is secured to a pin 22 which is journaled in 20 the arms of the fork 24 and said toe member is provided with the inclined face 25 which engages an inclined face 26 formed in the fork 23. A spring 27 acts to hold the toe member yieldingly in the position 25 shown in Fig. 1 with the face 25 thereof against the face 26. This spring is coiled about the pin 22 and has one end fastened to the fork 23, the other end being fastened to the pin. When the cam is rotating in the 30 direction of the arrow, Fig. 1, the pressure of the cam projections 12 against the toe

14 will keep the inclined face 25 against the inclined face 26 so that the toe and valve stem will act as a rigid member in opening the valve. If, however, the engine should 35 backfire and the cam should be rotated backwardly, the toe 14 will yield, thus preventing any damage from occurring. By means of this construction it is possible to use a slow-moving cam shaft which will 40 eliminate any possibility of the valve jumping and yet it is possible to have the valves opened and closed quickly.

My improved engine is especially useful in operating automobiles, air ships and other 45 devices where a high speed is desirable.

I claim:

In an internal combustion engine, the combination with a cylinder, of a piston 50 therein, a crank shaft to which the piston is connected, a valve having a valve stem, a toe pivoted to the valve stem and capable of swinging backwardly about its pivot, a cam shaft, a cam element thereon having a plurality of projections to engage said 55 toe, and thereby actuate said valve, a worm on the crank shaft, and a countershaft geared to the cam shaft and having a worm wheel thereon meshing with said worm.

In testimony whereof, I have signed my 60 name to this specification.

EARL F. KIMBALL.
